UNITED STATES PATENT OFFICE.

MICHAEL McNEIL, OF LOS ANGELES, CALIFORNIA.

INVALID-BED.

Specification of Letters Patent.

Patented May 1, 1917.

1,224,478.

Application filed November 22, 1915. Serial No. 62,902.

To all whom it may concern:

Be it known that I, MICHAEL McNEIL, a citizen of the United States, residing at Los Angeles, in the county of Los Angeles and State of California, have invented certain new and useful Improvements in Invalid-Beds, of which the following is a full and clear specification.

My invention relates to improvements in invalid beds, and is especially designed for use in hospitals or in sick-rooms and by persons who are bed ridden but still have the use of their hands.

My invention consists chiefly of a toilet fixedly located beneath a bed, and means located within reach of the occupant of the bed for flushing said toilet, a mattress upon said bed provided with an aperture having a sliding section, and means within reach 20 of the said occupant for opening and closing said aperture, the details of which will be more fully hereinafter explained and pointed out in the claims.

The object of my invention is to produce 25 a bed of the character hereinbefore referred to, which will be easy of operation, efficient in action and that can be manufactured cheaply.

With these objects in view I will describe 30 the device in its preferred form.

In the drawings Figure 1, is a side elevation of my improved bed complete.

Fig. 2, is a broken plan view of the bedstead and mattress, the working parts being 35 shown in dotted lines, likewise some of the framework thereof.

Similar characters of reference denote like parts in each of the views.

1, is the frame of the bed or what is better known as the bedstead, and 2, is the body of the mattress.

3, is an aperture in the center of the mattress into which is slidably fitted the section of mattress 4, said section resting 40 upon the supporting bars 5, which are secured to and held in place by the cross trusses 6, shown in dotted lines in Fig. 1, the said cross trusses 6, being secured in any approved manner to the frame of the 45 bed 1.

A bracket 7, is secured to the frame of the bed at 8, by screws, or otherwise, and a lever 9, is fulcrumed thereto.

One end of the lever 9, is operatively 50 attached to the mattress section 4, and its

opposite end is pivotally connected to the operating rod 10, which is guided in a suitable member 11, upon the frame 1, at 12.

A flexible apron of any suitable material forms a connecting cover 13, for closing 60 that portion of aperture 3, which would remain open when the mattress section 4, occupied that end of the aperture 3, nearest the head of the bed, this flexible apron 13, being attached to the body of the mattress 65 at one end and its other end being attached to the sliding mattress section 4, it will readily be seen that when properly attached at its two ends as above described, that it will be tightly stretched over the lower end 70 of the aperture 3, when mattress section 4, occupies its upper or closed position.

A toilet bowl 14, is located directly beneath the aperture 3, and is provided with both water supply and sewer connections 75 in the usual manner.

The toilet bowl 14, is provided with the ordinary flush tank 15, which is operated by the handled chain 16, in the ordinary 80 manner.

The operation of the device is as follows:

The occupant of the bed being unable to summon an attendant or not wishing to, as the case may be, simply supports himself upon his shoulders and feet enough to relieve the greater portion of his weight from the movable mattress section, operates the rod 10, in the proper direction to slide the mattress section 4, downwardly along the aperture 3, the flexible apron 13, dropping into the lower end of the aperture 3, and folding up therein, and leaving the upper end of the aperture 3, in open communication with the toilet bowl 14, through which the patient is able to accomplish his 85 or her requirements, the bowl being flushed at will by simply pulling the handled chain 16, in the ordinary manner, after which the aperture may again be closed by operating the rod 10, in the reverse direction from 90 that required to open it.

Having thus described my invention what I claim and desire to secure by Letters Patent is—

1. In an invalid bed, means forming a 105 bed having a vertical aperture, a toilet apparatus with the bowl under a part of said aperture, a bed section slidably mounted for horizontal movement in said aperture 110 to cover and uncover said bowl, and a han-

dle beside the bed and connected to said bed section for operating the said section to cover and uncover the bowl.

2. In an invalid bed, means forming a bed having a vertical aperture, a toilet apparatus with the bowl under a part of said aperture, a bed section slidingly mounted for horizontal movement in said aperture to cover and uncover said bowl, and a handle beside the bed and connected to said

bed section for operating said section to cover and uncover the bowl, and means within reach of the occupant of the bed for operating the said toilet apparatus.

In testimony whereof I affix my signature in the presence of witnesses.

MICHAEL McNEIL. [L. S.]
